PER MUNIF

United States Patent Office.

JOHN J. KIMBALL, OF NAPERVILLE, ILLINOIS.

Letters Patent No. 95,910, dated October 19, 1869.

IMPROVEMENT IN WATER-WHEELS.

The Schedule referred to in these Letters Patent and making part of the same.

To all whom it may concern:

Be it known that I, JOHN J. KIMBALL, of Naperville, in the county of Du Page, and State of Illinois, have invented a new and useful Improvement in Water-Wheels; and I do hereby declare that the following is a full, clear, and exact description thereof, which will enable others skilled in the art to make and use the same, reference being had to the accompanying drawing, forming part of this specification.

The object of this invention is to provide an improved construction of water-wheels, calculated to utilize the power of the water to a greater extent than is done by the wheels now in use, and, also, for more ready and economical application of the said wheels to the flume or penstock.

Figure 1 represents a vertical sectional elevation of my improved wheel, and

Figure 2 represents a horizontal section of the same.

Similar letters of reference indicate corresponding parts.

A represents the case or curb, having a closed top and vertical spaces B in the sides, forming chutes for conducting water to the buckets.

C represents an extension of the case below the wheel into the tail water, to produce a draught or suction on the discharging water.

The gate is composed of the ring D, having vertical wedge-shaped extensions E, fitted to the interior of the case A, and inclined on the inside from front to rear, toward the buckets of the wheel.

By turning this ring D, the gates are moved to open or close the passages B, and they have the effect to guide the water to the buckets in the most direct course, whether wholly or partly opened, so that the water acts with equal advantage, irrespective of the volume.

The wheel is composed of rims G and G', open at the top, arms H, projecting downward from the rim G, and buckets I, attached to the said arms, and to the rim G'.

By reason of the opening through the top, the upward pressure of the water is avoided, and the force of the water in the vertical direction is so nearly balanced as to allow the wheel to bear with its own weight on the step.

The said buckets are so shaped in the vertical parts as to receive the direct impelling force of the water, and in the angular parts below a reacting effect is produced, which is aided by the suction produced by the extension of the part C of the case below, into the tail water.

This wheel may be readily set into position in the bottom of a flume or penstock, by making a hole therein, for the reception of the extension C, to allow the flanges I to rest on the floor around the hole, where they may be secured by bolting or otherwise, as preferred.

Having thus described my invention, I claim as new, and desire to secure by Letters Patent—

1. The combination, with the case A, having the chutes B, of the ring D, and vertical wedge-shaped projections E, substantially as specified.

2. The combination, with the wheel, composed of the rings G G', vertical arms H, and buckets I, having vertical and inclined faces, of the tubular extension C of the case, substantially as specified.

JOHN J. KIMBALL.
